The ornamental design for the disc package for semiconductor wafers, as shown and described.

DESCRIPTION

FIG. 1 is a top front perspective view of a disc package for semiconductor wafers;

FIG. 2 is a front elevational view thereof, the undisclosed rear portion is a mirror image of the front;

FIG. 3 is a top plan view thereof;

FIG. 4 is a bottom plan view thereof; and,

FIG. 5 is a side elevation view thereof, the opposite side is a mirror image of the side shown.
